*Primary Examiner—Kay H. Chin***CLAIM**

The ornamental design for a modular system of recyclable waste receptacles, as shown and described.

DESCRIPTION

FIG. 1 is a top and front perspective view of a modular system of recyclable waste receptacles showing our new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a left side elevational view thereof;

FIG. 7 is a right side elevational view thereof;

FIG. 8 is a top and front perspective view of a second embodiment of the modular system of recyclable waste receptacle;

FIG. 9 is a top plan view of FIG. 8;

FIG. 10 is a bottom plan view of FIG. 8;

FIG. 11 is a left side elevational view of FIG. 8;

FIG. 12 is a right side elevational view of FIG. 8;

FIG. 13 is a rear elevational view of FIG. 8; and,

FIG. 14 is a front elevational view of FIG. 8.

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 13

FIG. 14
